UNITED STATES PATENT OFFICE.

ALBERTO MEMOLI, OF BROOKLYN, NEW YORK.

SEWING-MACHINE ATTACHMENT.

1,332,054.

Specification of Letters Patent. Patented Feb. 24, 1920.

Application filed April 24, 1919. Serial No. 292,293.

To all whom it may concern:

Be it known that I, ALBERTO MEMOLI, a citizen of the Republic of Brazil, and a resident of New York, borough of Brooklyn, county 5 of Kings, and State of New York, have invented certain new and useful Improvements in Sewing-Machine Attachments, of which the following is a specification.

My invention relates to sewing machine 10 attachments, and more particularly to an attachment for facilitating the sewing of an edge seam without basting the fabric in place.

Other objects, features and advantages of 15 the invention will appear more fully in the following specification and appended claims.

In order that the invention may be more clearly understood attention is hereby directed to the accompanying drawing forming 20 a part of this specification and illustrating one embodiment of the invention. In the drawing,

Figure 1 is a plan view illustrating the use of the invention in sewing an edge seam.

Fig. 2 is a view of the same partly in elevation and partly in section taken along lines 2—3 of Fig. 1, the fabric to be stitched being, however, omitted.

Fig. 3 is a plan view of the same arranged 30 for stitching an edge containing a reentrant angle.

Fig. 4 is a fragmentary front view on an enlarged scale.

To facilitate an understanding of the invention, a brief description will first be given 35 of the ordinary edge seam used in a garment such as a coat. In making such a seam, two layers of fabric are superposed with their front faces in contact and are then stitched 40 together by a machine close to their edges. The fabric article thus produced is then turned inside out so that the front or outer faces of the fabric are outermost, the edge portions of fabric being pressed down by the 45 fingers so as to bring the line of stitching substantially at the edge of the article. Fig. 4 shows the fabric in this condition and held in place to permit the sewing machine needle to stitch down the edge portion of the 50 article into final shape. In the said figure, *a* and *b* represent the two layers of fabric which have inwardly turned flange-like portions *c* and *d* connected by the line of stitching *e* which secures the two layers of fabric 55 together prior to the final stitching of the edge seam.

Ordinarily after the edge of the article is arranged as shown in Fig. 4 it is held in place during stitching by the sewing machine by basting. My invention obviates 60 the necessity of such basting and permits the fabric to be fed directly to the sewing machine needle for the outer stitching of the edge seam after the two layers of fabric have been turned so that the finished front 65 faces are outermost. My invention at the same time secures results in evenness of stitching which are superior to those obtained where the basting operation is employed.

Referring to the drawing, the invention 70 comprises a gage 1 for facilitating the positioning of the fabric with respect to the needle 2 so that the latter will operate upon the fabric article at a uniform distance from 75 the edge thereof, and a device whereby the edge of the article is gradually pressed down to desired shape as it is fed to the needle and held in such shape while it is being acted upon by the needle. This last named 80 device, as shown, is in the form of a tapering finger 3 projecting forwardly from the presser foot 4 of the sewing machine and extending a considerable distance forwardly of the needle 2. The finger 3 is arranged with 85 its axis parallel to the line of feed of the fabric through the machine and the guiding edge of the gage, the taper of the finger being such as to press the edge of the fabric with gradually increasing pressure to force 90 the same into shape for receiving the outer row of stitching from the sewing machine. The taper of the finger 3 also serves to press the fabric firmly over against the guiding edge of the gage 2, the edge of the fabric, as 95 shown in Fig. 4 being somewhat thicker than the portion arranged inwardly of the same. To facilitate proper positioning of the finger 3 with respect to the fabric and the gage 1, the finger is mounted so as to be laterally 100 adjustable. As shown, the finger 3 is mounted upon plate 5 which is adapted to slide laterally upon the presser-foot 4, the plate 5 being provided with an elongated slot 6 extending transversely to the axis of finger 3, and being secured to the presser-foot 4 by means such as the screw 7 passing through the slot 6. The presser foot shown is adapted to be attached to a sewing machine in place of the usual presser foot. It is provided at its upper end with a slot 8 through 110 which an attaching screw is adapted to be

passed, the slot furnishing vertical adjustment of the presser foot.

The gage 1, as shown, is made adjustable toward and away from the needle 2, as is usual. As shown, the gage 1 is provided with an elongated slot 9 extending at right angles to the line of feed of the sewing machine and is detachably secured to the base-plate 10 of the sewing machine by screws 11 and 12 passing through the slot 9, these screws being arranged so as to permit a movement of the gage toward and away from the needle. My improved gage is provided with a second gage member 14 which is movably mounted upon the gage 1 so that it may be arranged with its operative or guiding edge 15 in alinement with the operative or guiding edge of the gage 1 or moved into inoperative position as shown in Fig. 3 to facilitate sewing a seam in an edge containing a reentrant angle. When arranged as shown in Fig. 1, the gage members 1 and 14 provide a long guiding edge which is very effective in sewing a straight seam of considerable length; and when arranged as shown in Fig. 3, the part 14 is moved out of the way so as to form no obstruction to the projecting part of the fabric such as the lapel 7, the gage member serving as a guide for the fabric almost to the apex of the reentrant angle and the lapel passing into the angular recess of the gage 1 between the elongated portion 16 and the base portion 17. As shown, the member 14 is connected to the gage 1 by a screw 18 passing through a slot 19 in the member 14, which slot permits adjustment of the member 14 so as to bring edge 15 in alinement with the guiding edge of the gage 1. In use, the fabric article having been stitched as shown at e, the edge of the fabric article is pressed down somewhat between the fingers so as to bring the same approximately into shape and placed under the presser foot. The machine having been started, the fabric article is fed past the sewing machine needle 2, the edge of the article being guided by hand toward the gage and being pressed firmly against the latter by the finger 3 as the fabric is fed to the needle upon the movement of the usual feeding member, which is shown at 20 in Fig. 2. During this operation the finger 3 presses the edge portion of the fabric article gradually into shape and holds the same in shape while the needle 2 is operating upon the same; and an even seam is obtained at the edge of the article. Not only is the operation of basting the edge of the fabric eliminated but an additional saving of time is effected with my invention because there is no need of removing the basting after the edge has been sewed by the sewing machine. While I have shown one embodiment of my invention, it is to be understood that I

am not limited to this embodiment; and numerous changes and modifications may be made in the device herein shown without departing from the spirit of my invention.

What I claim as new and desire to protect by Letters Patent of the United States is as follows:

1. The combination of a fixed gage having a guiding edge and a projection of considerable length extending approximately parallel to said edge to press upon the material as it advances to a sewing machine needle and to hold the same compressed at a point in proximity to the sewing machine needle, said projection being tapered to cause the material to be gradually pressed to operative relation to the needle and gage to permit sewing an edge seam without basting. 75

2. The combination with sewing machine mechanism including a presser foot, needle, and feeding mechanism of a member carried by the presser foot and extending a considerable distance forwardly of the needle, said member being arranged to press upon the material as it advances toward the needle and to hold the same compressed in the vicinity of the needle, and a fixed gage adapted to be engaged by the edge of the material said member being adapted to press the material with gradually increasing pressure 95 toward said gage to facilitate the stitching of the material a uniform distance from the edge thereof to form an edge seam without basting. 85

3. The combination with sewing machine 100 mechanism including a presser foot, needle, and feeding mechanism, of a member carried by the presser foot and arranged to press upon the material with gradually increasing pressure as it advances toward the 105 needle and to hold the same compressed in the vicinity of the needle, and a normally fixed gage mounted for adjustment toward and from the needle, and adapted to be engaged by the edge of the material to facilitate 110 the stitching of the material a uniform distance from the edge thereof, said member being arranged to force said moving material against said gage to permit sewing an edge seam without basting. 115

4. The combination with sewing machine mechanism including a presser foot, needle, and feeding mechanism, of a projection carried by the presser foot and arranged to press upon the material with gradually increasing pressure as it advances toward the needle and to hold the same compressed in the vicinity of the needle, and a fixed gage adapted to be engaged by the edge of the material said projection being adapted to 120 press the material with increasing pressure toward said gage to facilitate the stitching of the material a uniform distance from the edge thereof to form an edge seam without 125 basting. 130

5. The combination with sewing machine mechanism including a presser foot, needle, and feeding mechanism, of a tapered finger carried by the presser foot and arranged to press upon the material with gradually increasing pressure as it advances toward the needle and to hold the same compressed in the vicinity of the needle, said member being adjustable toward and away from the needle, and a gage adapted to be engaged by the edge of the material to facilitate the stitching of the material a uniform distance from the edge thereof, said finger being arranged to force the moving material against the edge of said gage to permit sewing an edge seam without basting.

6. The combination with sewing machine mechanism including a presser foot, needle,

and feeding mechanism, of a member carried by the presser foot and arranged to press upon the material with gradually increasing pressure as it advances toward the needle and to hold the same compressed in the vicinity of the needle, said member being adjustable toward and away from the needle, and a fixed gage adapted to be engaged by the edge of the material to facilitate the stitching of the material a uniform distance from the edge thereof, said member being arranged to force said moving material against said gage to permit sewing an edge seam without basting.

In testimony whereof I have signed my name to this specification.

ALBERTO MEMOLI.
